UNITED STATES PATENT OFFICE.

FRANK COMEAU, OF LOUISBURG, NOVA SCOTIA, CANADA.

CLOTHES-PIN.

1,030,386.

Specification of Letters Patent. Patented June 25, 1912.

Application filed April 26, 1911. Serial No. 623,540.

To all whom it may concern:

Be it known that I, FRANK COMEAU, a subject of the King of England, residing at Louisburg, in the county of Cape Breton, Province of Nova Scotia, Dominion of Canada, have invented a new and useful Clothes-Pin, of which the following is a specification.

This invention relates to clothes pins.

10 The principal object of the invention is to provide a strong, simple, durable, and comparatively inexpensive clothes pin which may be easily and quickly manipulated and which is adapted to remain in either open 15 or closed position until the operator moves it to the other position.

With the foregoing and other objects in view which will appear as the description proceeds, the invention resides in the combination and arrangement of parts and in the details of construction hereinafter described and claimed, it being understood that changes in the precise embodiment of invention herein disclosed can be made 25 within the scope of what is claimed without departing from the spirit of the invention.

In the accompanying drawing forming a part of this specification, Figure 1 is a view in elevation of the clothes pin of the present invention in closed position; Fig. 2 is a sectional view through the construction illustrated in Fig. 1, showing the spring retracted and the jaws open; Fig. 3 is a section on the line Y—Y of Fig. 1; Fig. 4 is 35 a section on the line X—X of Fig. 1; and Fig. 5 is a perspective view of one of the jaws of the clothes pin.

Like reference numerals indicate corresponding parts in the several figures of the 40 drawing.

The clothes pin of the present invention comprises a body indicated generally by A, a pair of jaws indicated generally by B and C, pivotally connected with the body A and 45 adapted automatically to remain in either open or closed position, and a sliding U-shaped spring D adapted, when shoved in, as shown in Fig. 1, to hold the jaws B and C in the locked position, and when drawn 50 out as shown in Fig. 2, to hold said jaws positively in open position.

The body A of the clothes pin preferably is made up of a metallic casing 1, in which is mounted a filling block 2. The casing 55 1 as shown in Fig. 1 is provided with downwardly extending wings 3 in which are

pivoted the jaws B and C, as indicated at 4, said jaws being pivoted intermediate their ends. The jaws B and C are formed at their outer ends with meeting faces 5 which, when said jaws are in closed position, as shown in Fig. 1, contact with each other, and form a close fit. The inner faces of the jaws B and C are cut away, as indicated at 6 to provide a space to receive the 65 clothes line and clothes. The cut away portions 6 at their upper ends are shaped to produce right angular shoulders 7 which, when the clothes pin is in open position, as shown in Fig. 2, meet closely at their inner 70 ends so as to limit the distance to which the clothes pin can be fitted downward over the clothes line. In other words, the shoulders 7 serve as abutments to prevent the clothes pin from being moved too far with relation to the clothes line and the clothes. At their upper ends, the jaws B and C are formed with inner faces 8 which are arranged at such angle with relation to each other as to contact as shown in Fig. 2, when 75 the jaws are open, thereby limiting the extent of the opening movement of said jaws.

The spring D for holding the jaws B and C in either open or closed position preferably is U-shape and consists of the approximately parallel resilient arms 9—9 which at their free ends are bent or otherwise shaped to produce the limiting stops 10, the outer portions of which stops engage the lower edges of the metallic casing 1, when the pin is opened, as shown in Fig. 2, so as to limit the upward movement of the spring, and the inner portions of said resilient arms 9, as indicated at 10, engage the outer faces of the jaws B and C and slide thereon, so as to move said jaws from open to closed position and vice versa. Adjacent their upper ends, the arms 9 are curved outwardly as indicated at 12 to provide means to limit the downward movement of the spring D, as shown in Fig. 1, said outward bends 12 engaging the metallic casing 1 and preventing the spring D from being shoved down too far.

As shown in Fig. 4, the arms 9 slide in suitable grooves 14 formed in the filling block 2 and in suitable grooves 15 formed in the metallic casing 1, said grooves 15 being perforated, as indicated at 16 in Fig. 1 to reduce the friction on the spring arms 9.

Constructed as described, the operation of the clothes pin is thought to be obvious. By

grasping the casing 1, and pulling upward on the spring D, the clothes pin is opened and it remains in that condition until it is fitted over the clothes line and clothes, after 5 which the spring D is shoved down into the position shown in Fig. 1, thus locking the jaws B and C in closed position.

What is claimed is:

1. A clothes pin comprising a body, a pair 10 of jaws pivoted thereon, a U-shaped spring slidable on the body and extending above the body to form a handle for manipulating the spring, the free ends of said spring being slidable on the outer faces of the jaws 15 from points on one side of the pivots thereof to points on the other side of said pivots, said spring serving to hold the jaws positively in open or closed position, and means for limiting the sliding movements of said 20 spring, said limiting means engaging the spring when the spring is holding the jaws open.
2. A clothes pin comprising a body made up of a casing and a filling member, the 25 casing and filling member being formed in their sides with registering grooves, said casing being provided with downwardly extending wings, a pair of clamping jaws piv-

oted in said downwardly extending wings, said jaws having upper and lower sets of 30 faces arranged at an angle to each other, the lower set of faces being adapted to contact when the jaws are closed and the upper set of faces being adapted to contact when the jaws are open, said jaws also having cut 35 away inner faces formed at their upper portions with square shoulders adapted to aline with each other when the jaws are open to form a stop, and an approximately U-shaped operating spring extending through the 40 grooves in said casing and filling member, and slidable therein, said spring having limiting means at the upper and lower ends thereof to limit its sliding movement with 45 relation to said casing, the free ends of said spring bearing against the outer faces of said jaws and slidable thereon to move said jaws from one position to another.

In testimony that I claim the foregoing as my own, I have hereto affixed my signature 50 in the presence of two witnesses.

FRANK COMEAU.
